KEY CONTROLLED NUMERICAL DIGIT REGISTER EQUIPPED WITH DISCHARGE TUBE MEANS

Gerald Deakin, New York, N. Y., assignor to International Standard Electric Corporation, New York, N. Y., a corporation of Delaware

Application April 21, 1944, Serial No. 532,142

25 Claims. (Cl. 179—18)

1

This invention relates to new and useful improvements in switching systems of the type useful in controlling telecommunication.

The object of the invention is to provide a simple key-set controller selectively switching in circuit a relatively small number of resistances for controlling as many different switching operations as there are keys. For instance, a ten-button key set is provided with five resistances for controlling the performance of a desired one of ten switching operations.

In accordance with the present invention, a responsive or registering device is interposed between the key set and the switching device. It comprises electric discharge devices arranged in a number of groups less than the number of keys.

In the preferred embodiment here disclosed six identical vacuum tube circuits have their grids connected in multiple to one wire of a two-wire line connected with the key set. When the register is idle, the common lead is connected to ground through, e. g. a resistor of, e. g. 5,000 ohms. When the register is picked up, which in an automatic telephone system means that the line is closed to ground at the central office through the subscriber's set, the free end of a resistor of, e. g. 1,000 ohms also attached to this common lead is connected to a common battery of 48 volts. It will be assumed, for the purpose of determining the specific resistances and potentials used, that the maximum total loop resistance of a subscriber's line will not exceed 500 ohms and that the leakage resistance from the one line wire to ground or from the one line wire to the other will not be less than 25,000 ohms. Other resistance values could be used, but an insulation resistance of not less than 25,000 ohms is easily realized in any modern cable plant.

In operation, the potential of the common lead depends upon the value of the combined series line and key controlled resistance to ground in multiple with any leakage. An ample series of potentials may be obtained to operate any one of six tube circuits in multiple with the aforementioned leakage. The operation of one, two or three of these tube circuits makes it possible to select any one of ten digits, to change over from one selection to the other, or to effect a premature release should the calling subscriber hang up before the register is disconnected in the normal way after completing selection of the called line. The use of tube circuits in this manner eliminates timed circuits, timed relays or step-by-step means

2

now so generally used in dial-controlled register circuits.

In the drawings:

Figs. 1 is a diagram of a telephone substation circuit equipped with a key set;

Fig. 2 is explanatory of the order in which the key contacts are operated;

Figs. 3-8 show the mechanical arrangement of the key set, Fig. 3 being a section along 3—3 of Fig. 5, Fig. 4 a section along 4—4 of Fig. 6, Fig. 5 a section along 5—5 of Fig. 3, Fig. 6 a section along 6—6 of Fig. 5, Fig. 7 an end view of the key set with part of the wall broken away, and Fig. 8 is explanatory of the manner in which the contacts are operated;

Fig. 9 illustrates a telephone set equipped with a key controller;

Fig. 10 is a diagram of the register circuit;

Fig. 11 is explanatory of the functioning of the control circuit; and

Fig. 12 is a tabulation of the resistance values used and potentials applied to the register.

Subscriber's set circuit (Figs. 1, 2 and 9)

When the subscriber removes the handset from the switchhook, the ringer is disconnected and the *a* and *b* wires of the line circuit are connected through the usual induction coil, transmitter and switch-hook contacts. The ringer is disconnected so that the condenser shall not receive an appreciable charge between the keying of digits and thus produce unwanted potentials.

The mechanical details of the subscriber's keys will be disclosed below in connection with Figs. 3-8 after their electrical functions have been explained in connection with Figs. 1 and 2.

When any key 1-0 is depressed, contact 1 of the home contact nest closes and short-circuits the induction coil and transmitter. Immediately after that, contact 2 opens and removes a short-circuit around resistor RX and the five keying contacts C1 to C5. Resistor RX is adjusted individually at each station so as to make the combined series resistance of RX plus the line wire 45 LR in the loop to the central office 500 ohms $\pm 5\%$. To facilitate adjustment at the sub-station, it is proposed to use a plug-in radio type resistor for RX.

The above-mentioned operations take place 50 immediately upon the depression of any key. When any one of keys 1 to 4 is about $\frac{1}{4}$ depressed, one of the contacts C1 to C4 is momentarily opened by the key in passing, thereby momentarily introducing a resistor R1, R2, R3 or R4, as the case 55 may be, into the line circuit. Each resistor R1 to

R5 has a value selected to produce the certain potential changes when the resistance is cut in. The values are given in Fig. 12.

When the key is about $\frac{3}{4}$ of the way down, resistor R5 is momentarily introduced into the line circuit by the momentary opening of C5.

When the key is all the way down, the line loop includes RX and the line wires and the total resistance is therefore 500 ohms.

The key may be held down indefinitely but when it is released, it restores instantly to its normal position under the tension of a spring without switching in any of the resistances R1 to R5. The keys may be depressed very rapidly or very slowly; the speed of their operation is without effect on the responsive means.

When any one of the keys 5 to 0 is depressed, three contacts are momentarily opened instead of two, the first when the key is $\frac{1}{4}$ depressed, the second when the key is $\frac{1}{2}$ way down, and the third when the key is $\frac{3}{4}$ depressed.

The contacts which each key momentarily opens when it is depressed are indicated by the letters C1, C5, etc. placed immediately below the key button on the key contact diagram (Fig. 2). The contacts are listed top down in the order in which they are opened. It will be seen that contact C5 is always the last to open. It introduces resistor R5 into the line circuit which operates the change-over tube circuit in the register.

Should the subscriber hang up before completing keying, the line circuit will be opened and the shunt will be removed from the 5,000 ohm resistor R7 in the register circuit (Fig. 10), thereby permitting the potential of the common lead to increase to a maximum and operate the release tube circuit No. 6.

Key set assembly (Figs. 3-8)

One form of a ten-button key set is shown in these figures. It comprises ten key plungers 1 of which a rectangular portion pierces a housing 2 and is free to slide in said housing. The plunger is slipped through the housing from the bottom, after which button 3 is attached to it in any suitable manner. The lower part of the plunger 1 is round and over this part is slipped retractile spring 4, which rests against the bottom plate 5 of the housing and against the rectangular part of the plunger at the top. Thus the spring normally keeps the plunger in the position shown. A slanting wiper 6 projects from each plunger.

When any key is depressed, it longitudinally displaces two or three of five horizontal bars, B1, B2, B3, B4, and B5 in accordance with the setting of pins, P1, P2, P3, P4, etc., which project from the bars in patterns that determine the sequence of contacts C1—C5 that will be operated by the key. Each of the five bars engages at one end a contact C1 to C5 (see particularly Figs. 6 and 7). Part 7 is welded to bars B1 and B5 and operates the two outer contacts C1 and C5 when either bar is moved by a key. Part 8 projects from B2 and B4 and operates contacts C2 and C4. Bar B3 operates contact C3 direct. The other ends of the five bars rests against an insulated piece 9 attached to band spring 9 (see Fig. 4). Spring 9 keeps all the five bars in engagement with their corresponding C contacts. Movement of the spring 9 is limited by back stop 12. The five bars are held in position by slotted insulator supports 10 (Fig. 5) which are attached to the bottom of the housing 5.

Supported from the housing by any suitable 75

means, such as shown in Figs. 5 and 6, is a sliding plate 13 which engages the home contact nest 11 and is normally kept in the position shown by the tension of the spring nest. When any key is depressed, the slanting part 14 of the plunger 1 (Fig. 5) forces the sliding plate 13 to the left, thereby operating the home contact nest.

The arrangement of the pins in sliding bars B1 to B5 (see Fig. 8) agrees with the diagram (Fig. 2). For example, when key 6 is depressed and released, the following operations take place in the order listed:

a. Sliding plate 13 operates home contact nest 11.

b. When the key is about $\frac{1}{4}$ way down, wiper 6 engages pin P1 and forces bar B1 to the right, thereby opening contact C1. Almost immediately thereafter, part 6 releases the pin and bar B1 is forced back sufficiently by contact C1 to allow its closure.

c. When the key is about $\frac{1}{2}$ way down, bar B3 is similarly forced to the right through P3, and momentarily opens contact C3.

d. When the key is about $\frac{3}{4}$ way down, bar B5 is forced to the right by P5 and contact C5 is momentarily opened.

e. When the key is all the way down, bar B5 is released and contact C5 re-closes.

f. When pressure is removed from the key button, the plunger is quickly restored to normal by retractile spring 4. Wiper 6, however, engages the three pins in question from the under side, thereby forcing them to the left against common back stop 9. Contacts C1, C3 and C5 are thus not opened on the return stroke. As wiper 6 passes each pin, spring 9 restores the bar to normal.

g. When the plunger is fully restored to its normal position, sliding plate 13 resumes its normal position under the tension of the spring nest 11.

Since each key has three operating positions and since there are five bars, some of the pins are straight, others are bent upwards or downwards, as shown in Figs. 3 and 7. If this were not done, the sliding part 6 would in certain cases find the pins too close together and it would be difficult to close the first contact before opening the second. This is particularly true in the case of key 0 which operates bars B3, B4 and B5.

Subscriber's set assembly (Fig. 9)

One form of table set 25 equipped with handset 20 and key set 21 is shown in Fig. 9. To get the keys out of the way when removing and replacing the handset, and to obtain the required depth for the key set without disturbing the normal arrangement of ringer, induction coil and condenser attached to the base, the keys are back of the handset. The keys are guarded against accidental operation or damage by side and rear walls 22 and 23.

The depression 24 in front of the key set 21 and the outward slope of the wall 23 at the rear of the keys afford a means of picking up the table set without disturbing the handset.

Operation of the register (Fig. 10)

For the details of the register circuit, selectors, line finders and associated devices attention is directed to my copending application Serial No. 521,160, filed February 5, 1944. Here only so much is shown as is necessary for illustrating automatic means for variably responding to the actuation of the key set, for registering the response and transmitting it to selectors or the like

used, e. g. in the establishment of a connection between calling and called subscribers.

When the subscriber removes the handset 20, an idle register (Fig. 10) and a first line finder are connected with the calling line. When a digit keyed by the subscriber has been recorded, the "a" wire of the selector circuit is grounded and a potential is placed on the "b" wire so that the selection of the called line can be made. In the present case XR relays are substituted for the digit switches of my application Serial No. 521-160, filed February 5, 1944, in the same manner as in my copending application Serial No. 527,921, filed March 24, 1944, now Patent No. 2,433,345, dated Dec. 30, 1947.

When relay RAR releases, it opens the circuit of slow releasing relay LDR, thereby momentarily grounding both sides of the calling line for the purpose of discharging the energy stored in the line. When LDR makes its back contact, the V2 grids of the six triode circuits are connected to the "b" wire. RBR operates HTR. HTR connects resistor R7, also attached to the "b" wire, to the exchange 48 volt battery. The secondary winding of the dialing tone transformer TT is bridged across the calling line and the primary circuit is closed over a front contact of RBR. If required, filter F may be placed in the common valve lead to prevent false operation of the valve circuits due to possible undesirable potentials generated by the dialing tone circuit. HTR applies high tension battery to the valve circuits. RBR also operates R1R which controls release of the register circuit.

The six discharge tube means operate in the manner described in said applications. Each discharge tube means consists of a pair of triodes V1, V2, and a gas valve GV which controls an electro-mechanical relay GVR. The discharge tube means which in Fig. 10 are identified as tube circuits 1, 2, 3 and 4, are operated singly or in combinations of two as hereinafter specified, to respond to the setting of the ten keys at the substation and variably to operate in accordance therewith the digit register relay groups. The discharge tube means marked "Tube Ct. #5" controls the change-over from one digit to the next, and the discharge tube means marked "Tube Ct. #6" in Fig. 10 controls the release as will be hereinafter explained in greater detail. The operating potential for which each pair of triodes is set is shown in Figs. 11 and 12. When the potentials applied to the grids of a pair of triodes bear a predetermined relationship to one another, i. e. when they are the same, then the associated gas valve GV strikes and operates its GVR relay.

When the connection is established with the register, the subscriber's set is bridged across the line and the subscriber hears the dialing tone. The resistance of the loop circuit, as previously stated, is 500 ohms or less and the potential on a common lead (point E-1, Figs. 10 and 11) is well below the operating limit of any of the valve circuits.

When the subscriber depresses a key for the first digit, his induction coil and transmitter are short-circuited and RX (Fig. 1) is cut into the line circuit. The potential of point E-1 is now 12.7 volts (Fig. 12). This is the non-release condition during keying. If key 1 is depressed, then the next step is the insertion of resistor R1, which increases the loop resistance to 3500 ohms and the potential of the common tube lead to approximately 32 volts, whereupon the No. 1 pair of

triodes, the grid of one of which is permanently connected to this and only this potential, operates and fires the associated gas valve, all in the well-known manner. GVR1 operates. When key 1 is nearly fully depressed, it momentarily cuts in R5 (Fig. 1) and applies potential of approximately 18 volts, whereupon the No. 5 pair of triodes operates and energizes GVR5 (Fig. 10).

GVR5 grounds the armature of relay GVR1, 10 thereby causing XRI to operate. GVR5 also operates DTR which locks up over a front contact of R1R and disconnects the dialing tone. Shortly after GVR5 makes its front contact, it opens its back contact and releases HTR. HTR falls off, de-ionizes GV and releases GVR of tube circuits Nos. 1 and 5. When ground is removed from the winding of XR, the latter locks up over a front contact in series with the winding of TR1 and a front contact of RCR. TR1 operates and 15 transfers the tube circuits to the second set of XR relays over back contacts of TR2.

The second and following digits are keyed in the same manner as the first, tube circuits Nos. 1 to 4 or combinations of them being operated 20 according to the key depressed as indicated in the following table. The tube circuit No. 5 is always the last to be operated. It locks up the proper XR relay or relays and prepares immediately for the next selection.

Key Depressed	GVR and XR Relay Operated	PN-Potential Connected
1	1	PN-1
2	2	2
3	3	3
4	4	4
5	1+2	5
6	1+3	6
7	1+4	7
8	2+3	8
9	2+4	9
0	3+4	10

As explained in my copending applications, in multi-potential control systems like the one here disclosed, the selectors are started by the register and hunt for a potential corresponding to the one connected in the register. When the selector finds the desired potential its driving circuit is opened by the firing of the gas valve in the register.

Ordinarily the register is released upon the completion of selection. However, should the subscriber hang up before selection is complete, the line circuit is opened and the potential of point E-1 is increased to the maximum as indicated in Fig. 12, applying 40 volts to the grids and operating tube circuit No. 6. GVR6 opens the circuit of the release relay R1R which restores the circuit to normal.

60 What is claimed is:

1. In a telecommunication system, a plurality of lines, each having a multi-digit number, means including a plurality of stages of numerical selector switches for establishing a connection between a calling and a called line, a plurality of keys for each line, a normally inactive register comprising digit switching means for variably operating the selectors in accordance with the different digits of the called number, said register 65 comprising a plurality of electric discharge tube means less in number than the keys associated with a line, means for establishing a conductive connection from the keys to the tube means, a source of direct current potential, means controlled by the keys over the connection for se-

lectively operating the tube means from said source, and means controlled by the tube means for variably controlling the digit switching means.

2. The system according to claim 1, and in which the register comprises a digit switch for each digit, means controlled by the tube means for operating all the digit switches, and means controlled by one of the tube means for successively connecting the other tube means from one digit switch to the next.

3. The system according to claim 1, and in which one of the tube means operates upon each actuation of any key, and means controlled by the last-mentioned tube means for preparing the register for the next digit.

4. The system according to claim 1, and in which each line is provided with ten keys and the register four discharge tube means, means controlled by four keys for selectively operating the four tube means, and means controlled by each of the other six keys for operating two of said tube means in six different combinations.

5. The system according to claim 1, and in which each line is provided with ten keys and the register with four discharge tube means, means controlled by four keys for selectively operating the four tube means, means controlled by each of the other six keys for operating two of said tube means in six different combinations, and a fifth tube means in the register operable upon the actuation of any key, and means controlled by the fifth tube means for associating the four tube means with the digit switching means.

6. The system according to claim 1, and release means for the register controlled by one of the tube means.

7. The system according to claim 1, a plurality of resistances for each line, contacts controlled by the keys for selectively connecting said resistances in the connection for selectively operating said tube means.

8. The system according to claim 1, and a control grid for each tube means connected in multiple with said connection.

9. The system according to claim 1, and in which each tube means comprises a pair of tubes.

10. The system according to claim 9, and in which each tube is a triode, a multiple connection from the grids of one triode of each pair to said connection, and connections for applying different potentials to the grids of the other triodes of each pair.

11. In a switching system, a source of D. C. potential, a switch variably operable depending on the potential applied thereto, a plurality of two-wire lines, means for connecting a line with the source and the switch, keys associated with each line, home and keying contacts controlled by said keys, at least four different resistances connected in series with one another between the line wires over home contacts, a shunt normally closed around each resistance by a different keying contact, means for actuating the home contacts when any key is operated, and means controlled by each key for successively momentarily opening different keying contacts.

12. In a switching system, a source of D. C. potential, a switch variably operable depending on the potential applied thereto, a plurality of two-wire lines, means for connecting a line with the source and the switch, keys associated with each line, home and keying contacts controlled by said keys, five different resistances connected in series with one another between one line wire

and a normally open home contact, the latter connected with the other wire, a shunt normally closed around each resistance by a different keying contact, a sixth resistance for each line in series with the five resistances of a value approximately equal to the difference between the loop resistance of the line and a predetermined value, a shunt around the six resistances including a normally closed home contact, means for actuating the home contacts when any key is operated, and means controlled by the keys for successively momentarily opening different keying contacts.

13. In a switching system, a source of D. C. potential, a switch variably operable depending on the potential applied thereto, a plurality of two-wire control circuits, means for connecting one of the circuits with the source and the switch, ten keys associated with each line, a pair of normally closed keying contacts for each key, normally open and normally closed home contacts, five different resistances for each line connected in series with one another between one line wire and a normally open home contact, the latter connected with the other wire, a shunt normally closed around each resistance by a different keying contact, a sixth resistance for each line in series with the five resistances and having a value approximately equal to the difference between the loop resistance of the line and a predetermined value, a shunt around the sixth resistance and the keying contacts including a normally closed home contact, means for actuating the home contacts when any key is operated, a longitudinally movable plunger for each key, and means controlled by each plunger for successively momentarily opening predetermined keying contacts during its movement in one direction.

14. In a telecommunication system, a plurality of lines each having a multi-digit number, means including a plurality of stages of numerical switches for establishing a connection between a calling and a called line, a register for successively controlling the operation of said switches, a controller comprising ten keys associated with each line, each key adapted to variably operate the register in accordance with the different digits of the called number, a plurality of but less than ten discharge devices in the register connected to a common lead, key resistances, contacts controlled by the keys for connecting the key resistances in series with the line, the potential of the common lead depending upon the value of the combined line and key resistances in series to which said devices are responsive, a relay associated with each device and controlled by them, and a selector control circuit controlled by said relays in accordance with successive digits of the called number.

15. The system according to claim 14, and in which one of said relays controls the change-over of the register control from one selector to the next.

16. The system according to claim 14, and in which one of said relays controls the release of the register.

17. In an automatic telephone exchange system, a plurality of subscribers' two-wire lines each having a multi-digit number, means including a plurality of stages of numerical selector switches for establishing a connection between a calling and a called line, a plurality of registers for successively controlling the operation of said switches, ten keys associated with each line for variably operating a register in accordance with

the different digits of the called number, means for connecting a calling line with an idle register, six pairs of triodes in each register, one triode in each pair having its grid connected in multiple to a common lead to one of the wires of the calling line, a first connection to ground from the common lead over a resistance closed while the register is idle, a second connection from said common lead to battery over a resistance, key resistances, contacts controlled by the keys for connecting the key resistances in series with the line, the potential of the common lead depending upon the value of the combined line and key resistances in series to ground and in multiple with leakage resistance, a different D. C. potential connected to the grid of the second triode of each pair, a pair of triodes being adjusted to operate when the potentials applied to the grids of the triodes bear a predetermined relationship to one another, a relay associated with each pair of triodes and controlled by them, and a selector control circuit controlled by said relays.

18. In an automatic telephone exchange system, a plurality of subscribers' two-wire lines each having a multi-digit number, the loop and leakage resistances of a line having predetermined values, means including a plurality of stages of numerical selector switches for establishing a connection between a calling and a called line, a plurality of registers for successively controlling the operation of said switches, ten keys associated with each line for variably operating a register in accordance with the different digits of the called number, means for connecting a calling line with an idle register, six pairs of triodes in each register, one triode in each pair having its grid connected in multiple to a common lead to one of the wires of the calling line, a first connection to ground from the common lead over a relatively high resistance closed while the register is idle, a second connection from said common lead to battery over a relatively low resistance, key resistances, contacts controlled by the keys for connecting the key resistances in series with the line, the potential of the common lead depending upon the value of the combined line and key resistances in series to ground and in multiple with leakage resistance, a different D. C. potential connected to the grid of the second triode of each pair, a pair of triodes being adjusted to operate when the same potentials are applied to the grids of both triodes, a relay associated with each pair of triodes and controlled by them, and a selector control circuit controlled by said relays.

19. In an automatic telephone exchange system, a plurality of subscribers' two-wire lines each having a multi-digit number, the loop resistance of a line being less than about 500 ohms and the leakage resistance less than 25,000 ohms, means including a plurality of stages of numerical selector switches for establishing a connection between a calling and a called line, a plurality of registers for successively controlling the operation of said switches, ten keys associated with each line for variably operating a register in accordance with the different digits of the called number, means for connecting a calling line with an idle register, six pairs of triodes in each register, one triode in each pair having its grid connected in multiple to a common lead to one of the wires of the calling line, a first connection to ground from the common lead over a 5,000 ohm resistance closed while the register

- is idle, a second connection from said common lead to a 48 volt battery over a 1,000 ohm resistance, key resistances, contacts controlled by the keys for connecting the key resistances in series with the line, the potential of the common lead depending upon the value of the combined line and key resistances in series to ground and in multiple with the leakage resistance, a different D. C. potential connected to the grid of the second triode of each pair, a pair of triodes being adjusted to operate when the same potentials are applied to the grids of both triodes, a relay associated with each pair of triodes and controlled by them, and a selector control circuit controlled by said relays.
20. In an automatic telephone exchange system, a plurality of subscribers' two-wire lines each having a multi-digit number, means including a plurality of stages of numerical selector switches for establishing a connection between a calling and a called line, a plurality of registers for successively controlling the operation of said switches, ten keys associated with each line for variably operating a register in accordance with the different digits of the called number, means for connecting a calling line with an idle register, six pairs of triodes in each register, one triode in each pair having its grid connected in multiple to a common lead to one of the wires of the calling line, a first connection to ground from the common lead over a resistance closed while the register is idle, a second connection from said common lead to battery over a resistance, key resistances, contacts controlled by the keys for connecting the key resistances in series with the line, the potential of the common lead depending upon the value of the combined line and key resistances in series to ground and in multiple with leakage resistance, a different D. C. potential connected to the grid of the second triode of each pair, a pair of triodes being adjusted to operate when the same potentials are applied to the grids of both triodes, a relay associated with each pair of triodes and controlled by them, and a selector control circuit controlled by four of said relays.
21. The system according to claim 20, and in which one of said relays controls the change over to the next.
22. The system according to claim 20, and in which one of said relays controls the release of the register.
23. In an automatic telephone exchange system, a plurality of telephone substations, switching devices for connecting a calling with a called station, a circuit leading from each station towards the switching devices, a source of D. C. potential in said circuit, a set of keys, individual contacts controlled by each of the keys and a common contact controlled by all the keys, a device selectively operable under the control of the key contacts over said circuit, a ringer and a condenser in series in the circuit at each station, and means operable while any key is operated for disconnecting the ringer and condenser from the circuit.
24. In an automatic telephone exchange system, a plurality of telephone substations, switching devices for connecting a calling with a called station, a circuit leading from each station towards the switching devices, a source of D. C. potential in said circuit, a plurality of resistances at each station connected in the circuit, a set of keys, contacts short-circuiting the resistances controlled by the keys, a ringer, a condenser and

a normally closed home contact in series in the circuit at each station, said home contact short-circuiting all the keys, and means responsive to the actuation of any key for opening the home contact and maintaining it open while the key is operated.

25. In an automatic telephone exchange system, a source of D. C. potential, a plurality of telephone substations, switching devices for controlling the connecting of a calling with a called station, a two-wire circuit leading from each station towards the switching devices, means for connecting the source with the calling line, five resistances at each station connected in series in the circuit, ten keys at each station, contacts controlled by said keys short-circuiting the resistances, means controlled by the keys for selectively opening said contacts, a ringer, a condenser and a normally closed home contact in

series in the circuit at each station, said home contact short-circuiting all the keys and resistances, and means responsive to the actuation of any key for opening the home contact and maintaining it open while the key is operated.

GERALD DEAKIN.
